CLAIM

The ornamental design for a saw tooth, as shown and described.

DESCRIPTION

FIG. 1 is a perspective view of a saw tooth, showing my new design:

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top view thereof;

FIG. 7 is a bottom plan view thereof; and,

FIG. 8 is an enlarged detail view of Circled area in FIG. 1.

(Continued)

The broken lines shown in the drawings represent unclaimed environment only and form no part of the claimed design.

1 Claim, 4 Drawing Sheets
